UNITED STATES PATENT OFFICE.

WILLIAM W. GORDON, OF WASHINGTON, DISTRICT OF COLUMBIA.

COMBINED RAILWAY TIE, FISH-PLATE, AND CAR-REPLACER.

No. 896,378.

Specification of Letters Patent. Patented Aug. 18, 1908.

Application filed June 6, 1907. Serial No. 377,597.

To all whom it may concern:

Be it known that I, WILLIAM W. GORDON, citizen of the United States, residing at Washington, in the District of Columbia, have invented certain new and useful Improvements in a Combined Railway Tie, Fish-Plate, and Car-Replacer, of which the following is a specification.

My invention relates to a combined metallic railway tie, fish-plate, and car-replacer, and among the objects in view is to provide a device of the character referred to which shall be extremely simple in construction, possessing a minimum number of parts, effective in its operation and not liable to get out of order and also to provide such a device which can be quickly applied and taken apart when necessary.

With the above and other objects in view, all of which will appear from the following description when taken in connection with the accompanying drawings, my invention consists in the novel construction, arrangement and combination of parts, as described heretofore, shown in the drawings, and particularly pointed out in the appended claims.

In the drawings:—Figure 1 is a plan view of a portion of a track showing my invention applied. Fig. 2 is a vertical sectional view on the line 2—2 of Fig. 1. Fig. 3 is a transverse section on the line 3—3 of Fig. 2. Fig. 4 is a perspective view of that portion of my device comprising the tie and the outer flanged ends thereof. Fig. 5 is a perspective view of that portion of the device which is bolted to one of the end flanges of the tie and which serves, and coöperating with said end flange, to firmly secure a rail in position. Fig. 6 is an elevation showing a modified form of my invention applied to two rails, the latter being in section. Fig. 7 is a perspective view of one portion or section of the device. Fig. 8 is a perspective view of that portion of the device coöperating with the portion seen in Fig. 7. Fig. 9 is an elevation, partly in section, showing a further modified form of the invention. Fig. 10 is a perspective view of one portion of the device seen in Fig. 9. Fig. 11 is a perspective view of that portion of the device which coöperates with the portion seen in Fig. 10.

Referring particularly to Figs. 1 to 5 inclusive, my device comprises a metallic tie 1,

which is cut away at its opposite upper longitudinal edges as at 2 to form a contracted portion 3 intermediate the broader end portions 4, and said tie is also cut away upon its under side and longitudinally as at 5, to form the longitudinal parallel ribs 6. This construction provides a tie which is comparatively light in weight and yet sufficiently strong at those points where strength is required, and furthermore the ballast can be readily and efficiently tamped under and about the tie to firmly secure the latter in position.

Each end of the tie is provided with a flanged portion 7, each of which portions being constructed to serve the purposes of a fish-plate, and car-replacer, that is to say, it is undercut to provide a recess 8 within which fits the outer flange of the foot of the rail, and a recess 9 forming a shoulder against which abuts the tread of the rail, while intermediate the recesses 8 and 9 the flanged portions 7 are adapted to fit closely, or approximately so, against the web of the rail, sufficient space being left between for the expansion of the rail.

It will be noted that by the construction of the flanged portions of the tie, the same perform the function of fish-plates and furthermore, by the construction of tie described, the same really serves the purpose of a track gage, whereby the laying of a line of track is greatly facilitated and a considerable saving in time effected. The flanged portions 7 of the tie are further provided with the flanges 10, outwardly curved as shown, the upper edges of the flanges being slightly above the tread of the rail. The upper edges of the flanges are somewhat rounded and intermediate said flanges and the fish-plate portions of the tie, are portions 11 which in conjunction with the flanges 10, serve the purpose of a car-replacer. By curving the flanges outwardly, somewhat tapering throats are formed to facilitate the riding of the derailed car wheel up onto the portions 11, and the rounded edges of the flanges assist in this operation.

Adapted to coöperate with the fish-plate, and replacer portions of the tie, are the sections 12, each of which is constructed to serve as a fish-plate, and car-replacer, and for this purpose, each of said sections 12 is

provided with a flange 13 which curves inwardly, that is in a direction opposite to that in which the flanges 10 are curved. The upper edge of the flange 13 is about in 5 the same horizontal plane as the tread of the rails. Each section 12 is undercut as at 14 to form a recess, within which fits the inner flange of the base of the rail, and is also cut away as at 15 to form a recess for the wheel 10 flanges. Each section 12 is also provided with a portion 16 constituting a fish-plate and having a configuration to fit closely, or 15 nearly so, against the web of the rail, sufficient space being left between the two to allow for expansion of the rail.

Intermediate the flange 13 and the portion 16 of each section 12, are portions 17 onto which a derailed car wheel will be directed by the flange 13 in the act of replacing a 20 derailed car. The flange 13 and the portions 17 therefore constitute a replacer which coöperates with the replacer portion of the tie to effect the replacement of a de-railed car in a manner well known in this class of 25 devices.

The curved flange 13 forms tapering throats to facilitate the car wheel riding up onto the portions 17. In order that the 30 sections 12 might be firmly secured in position against the rails, I provide sections 12 with bolt holes 18 and also provide the flanged ends of the tie with similar holes 19, these holes 18 and 19 being so positioned, that, when the parts are in place, the holes 35 18 will register with the holes 19, and through said holes and holes in the rails I pass headed bolts 20, upon the inner threaded ends of which are mounted tightening nuts 21. It will be seen that by tightening 40 up the nuts 21 the sections 12 will be drawn tightly against the rail and the latter thus firmly secured between the fish-plate portions of the device, and spreading of the rails is absolutely prevented.

The car-replacers hereinabove described, by their construction do not present any 45 obstruction to the free running of the car wheels upon the rails and, therefore, my car-replacers do not constitute mere temporary devices for replacing a derailed car on the rails, as do the usual car-replacers as at present constructed, but are intended to always remain in position and form a permanent feature of the railway.

In order to give additional security against 50 any upward movement of the rails on the tie, I provide the broader end portions 4 of the tie with one or more recesses 22 (preferably two as shown), with which are adapted 60 to engage hook-shape lugs 23 provided on the sections 12 and when the sections 12 are in position, the lugs 23 engage with the under side of the tie and thus serve as a locking means for the sections 12 to prevent

any upward movement of the sections 12, 65 and, consequently, upward movement of the rails.

Each of the sections 12 of the device is cut away upon its under side as seen at 25, thereby forming a recess within which snugly 70 fits the broad ends 4 of the tie, and by reason of the shoulders 25', formed by cutting away the sections 12 as stated, fitting closely against the lateral edges of the tie, there is no danger of any strain being thrown 75 upon the bolts 20 upon the event of a car leaving the track, the wheels of which would strike against the end of the section 12.

Owing to the construction mentioned, all strain caused by the impact of the wheels 80 against the sections 12 would be sustained by the tie itself and therefore there is no danger of the bolts becoming broken. Were it not for the provision of the recess 25' receiving the tie, the bolts would have to sustain 85 all shock and might therefore become broken, which would, in such event, allow the rails to move inwardly.

Instead of constructing the tie as heretofore described and represented in Figs. 1 to 5, 90 I could construct the tie as seen in Figs. 6 to 10, wherein I show the tie 26 as being made in two parts adjustably connected together. In this construction, the central portion of the tie intermediate the broad ends 27 there- 95 of, is reduced to form a cylindrical shank 28, and the tie is divided to form the two similar sections 29 and 30. The reduced portions of the tie sections are threaded reversely and are adjustably connected together by means of a 100 turn buckle 31, by means of which the two sections of the tie may be adjusted toward or from each other within certain limits. This construction is desirable for maintaining at all times close and firm engagement of the 105 fish-plate portions of the tie with the rails. In other respects the construction of the ends of the tie to provide the fish-plate, and car-replacer, is the same as that described with reference to Figs. 1 to 5, and the construc- 110 tion of the sections 32, which coöperate with the modified construction of tie, is also similar to the construction of the sections 12 seen in Figs. 1 to 5.

The parts seen in Figs. 6, 7 and 8 are connected to the rails in a manner similar to that seen in Figs. 1 to 5, that is to say, by means of bolts adapted to pass through aligned openings 36 and 37 provided in the sections 32 and the coöperating portions of the tie sec- 120 tions, as well as through openings provided in the rails which align with the openings 36 and 37.

In Figs. 9, 10 and 11, the construction of the device is similar to that seen in Figs. 6, 7 125 and 8, with the exception that the sections 38 are provided with recesses 39, within which are contained nuts 40 on the tightening bolts

41. By this arrangement there is little danger of the bolts working loose, and instead of having the bolts lie horizontal as seen in Fig. 9, I may so locate the bolt openings, that, 5 when the bolts pass therethrough, said bolts will lie in a slightly inclined position, the end of the bolt which carries the nut 40 being slightly lower than the outer headed end of the bolt. By so inclining the bolts there will 10 be less tendency of the same to turn and work loose. In the construction seen in Figs. 9, 15 and 11, I dispense with the car-replacing portions and it will be understood that I could do this also with the construction seen in Figs. 1 to 5.

If desired, the constructions seen in Figs. 6 to 10 could be used with the ordinary wooden tie, the improved tie being clamped in any desired manner upon the ordinary 20 wooden tie.

While I have described my device as being a combined railway tie, fish-plate, and car-replacer yet it will be understood that I could dispense with the tie portion and use 25 simply the combined fish-plate, and car-replacer portion, or I could use the car-replacer portion alone, or I could use the tie portion alone.

What I claim is:—

30 1. A combined metallic railway tie, fish-plate, and car-replacer.

2. A metallic railway tie cut away upon its opposite sides to form a narrow body portion and having two integral longitudinal ribs laterally spaced from said narrow body portion 35 and an integral longitudinal rib beneath said body portion.

3. A device of the character described comprising a tie having integral flanged portions 40 at its ends forming fish-plates, each of said flanged portions being constructed to engage with the head of a rail and to fit between said head and the base of the rail on the outer side of the latter, and fish-plate sections constructed to engage with the head of a rail and to fit between said head and the base of the rail on the inner side of the latter, said fish plate sections having hooked lugs adapted 45 to pass within recesses in the tie and engage with the latter, said flanged portions of the tie and said fish-plate sections having bolt openings adapted to align in the manner specified.

50 4. A device of the character described, comprising a tie having integral flanged portions at its ends, each of said portions being constructed to engage with a flange on the base of a rail and also to engage with the head of the rail and to fit between said head and the base of the rail and the flanged portions 55 of the tie being also constructed to constitute car-replacers.

5. The combination with the rails having bolt openings of a tie having integral flanged

portions at its ends, each of said portions constituting a fish-plate section engaging with the flange on the base of a rail and also with the head of a rail and fitting between the head and the base of the rail on the outer side thereof and having bolt openings, fish-plate 65 sections each engaging with the flange on the base of a rail and with the head of the latter and fitting between said head and the base of the rail on the inner side of the latter, said fish-plate sections having bolt openings, the 70 various fish-plate sections being constructed to form car-replacers, and bolts passing through the openings of the fish-plate sections, the rails and the flanged portions of the tie to secure the parts together. 75

6. The combination with a tie having longitudinal ribs on its under side and having integral flanged portions at its ends adapted to engage with the rails upon the outer side thereof and constituting fish-plates, said tie 80 having recesses in its body portion, of fish-plate sections adapted to engage with the rails on the inner sides thereof and having depending hooked lugs adapted to engage within the said recesses. 85

7. A combined fish-plate and car replacer constructed integral with each other.

8. A combined fish-plate and car replacer constructed integral with each other and having bolt-openings therein. 90

9. The combination with the rails, of a combined fish-plate, and car-replacer bolted to said rails.

10. The combination with the rails, of a combined fish-plate and car replacer constructed integral with each other, and arranged upon the outer sides of the rails, a combined fish-plate and car replacer constructed integral with each other and arranged upon the inner sides of the rails and 100 means for securing the parts together.

11. A combined fish-plate, and car-replacer comprising two coöperating portions adapted to be arranged upon opposite sides of a rail and provided with bolt openings adapted to 110 align.

12. The combination with a rail, of a car-replacing device comprising two coöperating portions arranged one upon the inner side of the rail and one upon the outer side of said rail, each of said portions being constructed to re-rail a car traveling in either direction, and means securing the said coöperating portions to the rail. 115

13. A car-replacing device comprising two coöperating members, each having a portion adapted to fit against the side of a rail and also having a re-railing flange constructed to re-rail a car traveling in either direction and a portion intermediate the flange and the 125 first-mentioned portion, all for the purposes set forth.

14. The combination with a rail, of a car-

replacing device comprising two coöperating portions arranged one upon the inner side of the rail and one upon the outer side of said rail, and bolts passing through alined openings in the said portions and the rail.

15. The combination with a rail, of a car-replacing device comprising two coöperating portions arranged one upon the inner side of the rail and one upon the outer side of said rail, each of said portions being provided

with a re-railing flange constructed to re-rail a car traveling in either direction, and bolts passing through alined openings in the said portions and the rail.

In testimony whereof I affix my signature 15
in presence of two witnesses.

WILLIAM W. GORDON.
